ABSTRACT

The invention relates to a water-borne craft of the hydroplane type which is capable of ocean travel at high speed while simultaneously maintaining a high degree of stability and a horizontal aptitude to the craft. The craft is supported by a support assembly in the form of a plurality of vertical structure supports which have a pair of roller shaped floats positioned to each vertical support through means of a rocker assembly pivotally connected to the vertical supports and mounted for reciprocating movement up and down the support, and shock absorbing means carried by said support to provide a shock absorbing action upon the vertical reciprocation of each pair of floats. A propulsion unit for the craft includes a controlled water inlet means, multi-stage combustion zones for generation of steam and combustion products, a turbine means for generation of electrical power, and jet nozzle means for generation of the required propulsive force.

HYDROPLANE CONSTRUCTION

RELATED APPLICATION

This application is a division of application Ser. No. 570,606, filed Aug. 5, 1966, now U. S. Pat. No. 3,592,154.

The present invention relates to water-borne craft which can traverse oceans that accumulate high waves, and more specifically to such vessels which are capable of traversing the seas at high speeds while simultaneously maintaining such vessels at a high degree of stability and horizontal attitude by means of a series of roller shaped floats within rocker assemblies, the fulcrums of which are provided with hydraulic shock absorbers, and which are independent suspension units to support the draft in a flexible manner while conforming to, and absorbing, the shocks imparted by the high waves.

In order that the invention may be fully understood, a preferred embodiment thereof will now be described with reference to the accompanying drawings.

FIG. 1 is a side elevation of a multiple floated hydroplane according to the present invention, the basic craft being therein presented.

FIG. 1A is an enlarged detailed fragmentary cross-section of a roller float's hydraulic assembly shown in FIG. 1.

FIG. 2 is a front elevation of the basic craft shown in FIG. 1.

FIG. 3 is a rear elevation of the basic craft shown in FIG. 1.

FIG. 4 is a plan view of the basic craft shown in FIG. 1.

FIG. 5A is a side elevation of the initial water, air and oil inlet assemblies within one of the propulsion units, and also illustrates the ignition system and first and second phases of combustion.

FIG. 5 is a front elevation of an initial water inlet assembly for one of the propulsion units made in accordance with the present invention.

FIG. 6 is a side elevation of the third and fourth phases of combustion within one of the propulsion units and also illustrates the turbine and generator assembly with associated multiple coils and distributors, with turbo-alternators for ultra-high frequency to the spark flow circuitry in the electrical infusion of phase six, within one of the propulsion units.

FIG. 6A is an end or transverse elevation of the layout of the generators around the central gas eflux tube from the turbine, within one of the propulsion units.

FIG. 7 is a side elevation illustrating the fifth, sixth and seventh phases of combustion, within one of the propulsion units.

FIG. 7A is a cross-sectional view of one of the helical installations of the electrical spark electrode assemblies inside the electrical infusion tube and within one of the propulsion units.

FIG. 8 is a side elevation of the front two-thirds of one of the propulsion units within the convertible arrangement for the provision of an electrical generating and/or pumping plant.

FIG. 8A is a transverse end elevation illustrating the connection of a propulsion unit to an immersed power plant.

FIG. 9 is a side elevation of the aft or final one-third portion of a propulsion unit arranged for prior connection to the plant's tubular housing assembly, which con-

tains the main turbine-to-generators and/or pumps for the plant installation, and further illustrates the forward portion of the plant tubular housing, as connected to the thrust jet orifice, of one of the propulsion units.

FIG. 9A is a side elevation of the remainder of the plant's tubular housing illustrating the insulated water jacket and main turbine coupled to generators and/or pumps installed within, and also the power output cables and/or pumped liquid output pipes at the rear.

FIG. 10 is a plan view of the composite craft as constructed utilizing a plurality of the basic craft to provide a much larger craft and of greater flexibility to counteract larger waves on oceans in stormy conditions.

FIG. 11 is a side elevation of the composite craft shown in FIG. 10.

FIG. 12 is a rear elevation of the composite craft shown in FIG. 10.

FIG. 13 is an end elevation cross-sectional view of the triple phase distribution of electrical current supply for each twin-spark electrode assembly.

FIG. 13A is a plan diagram of the triple phase power distribution circuit with modulation for each twin-spark electrode assembly.

FIG. 14 is a longitudinal cross-sectional view of the boost unit's intake, turbine, turbo-alternators, couplings and distributors as driven.

FIG. 15 is a longitudinal cross-sectional view of the boost unit's continuation showing expansion chamber, electro-infusion, final combustion chamber, outlet venturi and thrust gas eflux.

BASIC SUPPORT ASSEMBLY

Referring to the drawings, FIG. 1 illustrates the general mechanical and structural layout of the invention whereby the twin-mounted roller floats 1, as shown in FIGS. 2 and 3, are arranged in longitudinal alignment, with each pair of floats being contained between each transverse pair of rocker members, as best shown in FIG. 1. The fulcrums of the rocker members are provided with pivot pins 3 on which are also mounted the base members 4 of the hydraulic shock absorbing assemblies, this being shown in greater detail in FIG. 1A.

The base members 4 and the pivots 3 may move freely in a vertically reciprocal manner within guide slots 6 which are formed by guide members 7 positioned within the vertical structure supports 8, this arrangement being illustrated in FIGS. 1, 1A, 2 and 3.

Referring to FIG. 1A particularly, it is seen that each piston shaft 9 is connected at one end to its respective base member 4 with the opposite end of each being connected to the corresponding hydraulic piston 10 which is surrounded circumferentially by the hydraulic cylinder 11 within which the hydraulic fluid 12 is carried.

The uppermost extremity of each of the hydraulic assemblies is connected to the equalizing pressure tubes 13 shown in FIG. 1 which, in turn, are connected to the central spherical dampening chamber 14. A flexible diaphragm member 15 is positioned in the dampening chamber 14 in order to allow pneumatic air pressure 16 to fluctuate upon its upper surface in accordance with the desired air pressure imparted thereto from the dampening pneumatic pump 17 which is shown in FIG. 4.

BASIC CRAFT STRUCTURE

Referring to FIGS. 1, 2, 3 and 4 wherein the basic craft structure is shown, it is seen that the main struc-

ture of the basic craft made in accordance with the present invention includes longitudinal decking members 18 joined at right angles to the transverse members 19, while the vertical diagonal bracing beams 20 serve to connect the vertical structure supports 8 to the longitudinal members 18 in a rigid manner. Transverse beams 21, as shown in FIGS. 2 and 3, are similarly connected between the vertical structure supports 8 and also the transverse members 19 and then cross-braced by vertical diagonal bracing beams 20 similar to those shown in FIG. 1.

Referring specifically to FIG. 4 only, it is seen that the structural supporting framework for the decking members 18 is completed by the interconnection of diamond-lattice diagonal bracing beams 22 longitudinally, whereupon further decking plates and/or planks or panels may be affixed as desired.

Referring specifically to FIG. 1, accommodation decks 23, positioned above the main deck 24, may be constructed in any desired manner and material so long as the materials employed are of lightweight density, such as aluminum coated with fiberglass or perspec and held by a suitable bonding adhesive, such as Araldite. The structure should be such that ample window areas are present in the accommodation deck.

As illustrated in FIG. 1, only a certain portion of the main deck area amidships is allocated for the liquid oxygen and liquid hydrogen processing plants 25 and 26 respectively which will utilize spent insular water 41. These processing plants may well be any orthodox installations of established design and manufacture and chosen to meet the requirements to support the performance of this craft as desired.

Referring again only to FIG. 1, the side plating 27 in conjunction with the semi-circular splash guard plates 28 serve to form the housing compartments 29 within which the heavy gas oil tanks 30, the paraffin tanks 31, the kerosene tanks 32 and the electric starting and storage batteries 33 are positioned. Bilge and/or fresh water tanks 34 may also be similarly housed in housing compartments 29.

Referring to FIGS. 1, 2 and 3, it is seen that the vertical rudder shaft locating beams 35 are affixed transversely in a horizontal manner at both extremities of this basic craft and are secured to the vertical structure members at these locations. The vertical rudder shafts 36 proper are installed thereto within bearings 37 at locations centrally between each pair of propulsion units 38, as shown in FIGS. 2 and 3, with the rudders 39 being situated at the lowest extremities of the respective rudder shafts 36.

Referring again to FIG. 1, the spent insular water delivery tubes 40 shown therein actually serve to guide the insular water flow 41 from their respective activated propulsion systems 42 after the insular water therein has served its cooling purposes. These delivery tubes 40 are installed to feed the shipboard distillation plant 43 which is of any desirable design of established manufacture and which functions to process the necessary fresh water 44 from the insular sea water 41 for the benefit of crew and passengers travelling on board. Adjacent to the distillation plant 43, the aforementioned liquid oxygen processing plants 25 and liquid hydrogen processing plants 26 are mounted.

PROVISION FOR REVERSE DIRECTIONAL MOVEMENT OF THE BASIC CRAFT

Referring further to FIGS. 1, 2 and 3, it is seen that the propulsion systems 42 are so installed as to provide rearward-thrust and therefore forward directional movement to the craft from a plurality of these systems which deliver their respective spent insular water 41 at the rear, via the delivery tubes 40. A further plurality of propulsion systems 42a are so installed, conversely, to impart thrust at the front of the craft which provide rearward directional movement to the craft. Hence systems 42a deliver their respective spent insular water 41 from the front of the craft via their delivery tubes 40 at 15 the front of the craft. Referring now to FIGS. 1 and 2 only, to facilitate the choice of directional movement to the craft, all the propulsion systems are fitted with hinged blanking-off cone shaped caps 55 at their inlet and outlet extremities. In order to blank off the unwanted systems which are not used for the direction of the craft as desired, for example when the craft is set for moving in a forward direction, the rearward propulsion systems 42 are blanked off at their inlet and outlet extremities by their respective hinged cone caps being 20 pre-set in their closed positions 45a to seal off entry and exit of inlet water and outlet eflux of thrust steam-gas respectively.

Referring to FIG. 3, conversely, when the craft is to be moved in a rearward direction, all the forward propulsion systems 42a are blanked off by their respective hinged cone caps being pre-set in the closed position 45a while the rearward propulsion systems 42 are actively engaged with their respective hinged cone caps 25 in the open position 45b, as shown in FIG. 1. All cone caps are fitted with drainage facilities consisting of an electrically driven pump 46 for scavenging sea water via delivery pipe 47, as shown in FIG. 1.

PROPELLION SYSTEMS

The propulsion means for this type of craft consists of a primary ignition system and a secondary ignition system. The primary ignition system utilizes an atomized mixture of blown air, pumped heavy gas oil and pumped water from the front of the craft, which mixture is imparted to a plurality of electrically heated plates, with the water being used primarily in the form of an atomized spray to intersperse the molecules of the oil in order to place the mixture in condition for an incandescent combustion flowing rearward. The resultant pressurized gas and steam mixture is allowed to pass directly into the initial combustion chamber, for further pressurization via a convergent-to-divergent diffuser tube to complete the first phase of combustion.

The second phase of combustion is afforded by the continuation of the gas and steam flow into a divergent-to-convergent diffuser tube. Into this tube, at the initial points of divergence, compressed air is pumped into the gas and steam flow while a paraffin grade fuel is injected simultaneously into the flow at adjacent points to those of compressed air entry. Furthermore, since the entire combustion systems are surrounded by a jacket of insular water which flows from fore to aft, a small quantity of this warm water is taken and pumped into this second phase of combustion at points of entry adjacent to those of the compressed air and paraffin. Thus the second phase of combustion is completed

when compression is achieved within the convergent confines of this tube.

The third phase of combustion takes place within a further divergent-to-convergent diffuser tube, in a manner similar to the second phase. The difference is that the compressed air, insular water and a high grade kerosene fuel are placed at this phase at a higher pumped pressure. The resultant pressurized gas and steam flowing therefrom is allowed to flow directly into an axial flow turbine of established design and manufacture which is directly coupled mechanically to a power take-off gear and shaft assembly in sun and planet formation, while the jet efflux from the turbine is delivered through a tube in the center of the latter assembly. The planet gear shafts are coupled directly to electric generators, respectively, each of which is contained within its own waterproof housing since the insular water is allowed to flow therearound to protect its metallic components from overheating. The efflux tube containing the gas/steam flow from the turbine is also connected to a tubular after-burner assembly of established design and manufacture wherein an additional supply of compressed air and kerosene is forcibly injected. This arrangement constitutes the fourth phase of combustion.

Immediately aft of this assembly, a further calibrated supply of insular water is forcibly injected into the gas flow in a parallel direction and within an expansion combustion chamber of hemispherical shape and construction. This constitutes the fifth phase of combustion.

The sixth phase of combustion consists of a convergent-to-divergent diffuser tube connected immediately aft of the expansion chamber, to direct the steam/gas flow rearwards at a higher speed into a tube within which is installed a plurality of heavily insulated electrical spark electrodes arranged in helical alignment so as to impart a sufficiency of electrical activation and heat energy to the steam/gas flow. The sparks are directed from fore to aft.

The seventh phase of combustion consists of a further hemispherical chamber which is connected directly onto and immediately aft of the latter tube and the resultant pressurized gas flow passed thereto accepts the intermittent injection of liquid oxygen and liquid hydrogen which is forcibly fed thereto in parallel flow and in streams of atomized spray with respect to the directional flow of the pressurized gas. This flow of the gas is rearward into a convergent infusion nozzle which increases the pressure before passing into a final venturi to impart thrust prior to final efflux from a tail pipe at an ultra-high speed.

The liquid oxygen is supplied from a processing plant on board the craft utilizing the surrounding air. The liquid hydrogen is processed on board utilizing the remainder of the warm insular water which is fed from the rearmost extremity of the propulsion system by a feed pipe after this water has served its insulating purpose.

This type of craft made in accordance with the present invention and as illustrated comprises a plurality of propulsion units in parallel longitudinal alignment below the surface of the ocean while the plurality of roller shaped floats within their respective rocker assemblies are situated between the propulsion structures and yet roll on the surface of the ocean while supporting the entire weight of the craft with its superstructure

containing the controls, primary fuels, electric batteries and the payload, in addition to the life saving equipment.

Ancillary equipment includes extra turbines and electric generators and/or pumps installed within immersed tubes to utilize the final jet effluxes when the craft is installed as an off shore power plant.

Replicas of this invention may be pivotally connected by torsion beams to form a larger composite craft for a higher degree of stability, speed and payload, with a more efficient capability to negotiate and traverse oceans having accumulated water of outstanding proportions in enormity.

It is intended and is within the scope of the invention that the greatest proportion of the total thrust output propulsion force be derived from the water upon which the craft is borne and the air around and above it while the primary fuels may be utilized in minimal quantities when the maximum operating temperatures and pressures are obtained.

Reference is now to be had to FIGS. 5, 5A, 6, 6A, 7 and 7A wherein illustrative propulsion means for this type of craft made in accordance with the present invention is shown.

Referring now to FIGS. 5 and 5A specifically, the primary ignition system shown therein utilizes an atomized mixture of blown air 48 being driven from the intake blower 50 into the initial air intake tube 49. The blower 50 is electrically driven by the air input fan motor 51. The moving air stream 48 conveys the globules of heavy gas oil 52 which is pumped into the air intake tube 49 from the oil delivery pipe 53 by means of the electrically driven oil pump 54 located below the oil supply tank 30, which is below the main deck (see FIG. 1 only). The resultant mixture of air and oil is thus fed downwards through the intake tube 49, below the surface of the water upon which the craft is borne, into the main mixing gallery 56, wherein the perforated cone 57 provides multiple water jets 57a. The mixture is utilized therefrom in an atomized condition to intersperse the globules of the oil in order to separate the oil molecules for further advancement to create this total mixture of air, oil and water so as to render them to be more amenable for an incandescent combustion. The initial ignition occurs when a red glow heat is imparted from a plurality of cone shaped electrically heated plates 58 and/or electrically heated concentric coils of tubes, rods or wires 59 as optionally chosen for the initial ignition medium or means.

This initial ignition arrangement is installed within the entry area of the initial combustion chamber 60 in order to provide and to direct the resultant pressurized gas and steam mixture 61 for further pressurization via a divergent-to-convergent diffuser tube or cone 62 to complete the first phase of combustion.

It is noted, however, that the water upon which the craft is borne is utilized also as a coolant in the form of insular water 64 passing within the gallery between the combustion chambers 60 and the outer cylindrical jacket 65. The actual flow rate and speed of this insular water may be regulated by the insulating water flow valve 66 which consists of a plurality of cones or parabolas 67 into which are cut apertures or voids 68 in order that when the cones or parabolas are installed in an alternately fixed and rotationally movable sequence it is then possible to variate the flow of insular water by the amount of the apertures or voids 68 being closed

over by structural areas 69 of the adjacent cones or parabolas 67 when rotation takes place.

The means of rotation of the valve 66 is provided by worm-wheel 70 which is affixed to the boss 71 of the rotationally movable cones or parabolas 67 in conjunction with the drive worm 72 positioned with its electric drive, shunt-wound and two directional motor 73 in an adequately sealed housing 74 inside the insular water gallery 64. The controls thereto are installed within the bridge or control cabin of the craft.

The actual input water 75, utilized as an aid to combustion, enters the propulsion unit via the water inlet tube 76 within the nose assembly 71 of the unit. Onto the interior extremity of this tube is installed the initial input water supply valve 78 which is merely an orthodox supply cock which fulfills its functional purpose in admitting a liquid, or closing the flow of a liquid, by the inner barrel member being turned throughout an angle of 90°. To this end the operating lever 79 on this valve is shown in the form of either pivot rods and bell cranks or a push-pull rod in a holster tube. These control levers, through appropriate linkage, may be connected to the bridge or control cabin as desired or optionally chosen. In order to deliver a measured rate of flow to the input water 75, an electrically driven accelerator pump 80 of established manufacture and design is installed adjacent the input water supply valve 78 and prior to the input water being fed to the multiple spray jets 57a to aid combustion, as hereinbefore described.

A further diffuser tube 81, of divergent-convergent design, is installed on the convergent delivery periphery of the first phase diffuser 62. Into the tube 81 at the initial points of divergence, compressed air 82 is pumped via air pipes 83 through their respective injectors 84 by compressor pumps on the main deck of the craft into the gas and steam flow 61. A paraffin grade fuel 85 is injected simultaneously into the flow via injectors 86 at adjacent points to those of compressed air entry. Furthermore, since the entire combustion systems are surrounded by the jacket of insular water 64, a small quantity of this warm water is allocated to be pumped into this second phase of combustion by water pump 87 and water injectors 88 at points of entry adjacent to those of the compressed air and paraffin with all of the streams being parallel to the gas/steam flow 61. Thus the second phase of combustion is completed by the latter when compression is achieved within the convergent confines of this tube.

Referring now to FIG. 6, the third phase of combustion takes place within the divergent-to-convergent diffuser 89 wherein kerosene pumped from the main deck is delivered via the kerosene supply pipes 90 to their relevant kerosene injector nozzles 91 in order to provide an atomized kerosene spray 92 in the form of a flowing mist parallel to the flow of the gas/steam stream 93. At the same time, a simultaneous injection of pumped insular water is imparted into this gas/steam stream via the water injectors 94 and also as a parallel mist flow. The force required to achieve this is provided by the electrically driven water accelerator pumps 95. Simultaneously therewith, an influx of compressed air 96 is imparted into this diffuser 89 via the compressed air supply pipe 97 but at a greater flow rate and velocity than that which occurs within phase two of the combustion system as already described hereinbefore. This air supply is also obtained from the main deck from an air compressor of conventional design

and manufacture. When these three elements of kerosene, air and water are thoroughly intermixed within an equilateral rearward flow and burned simultaneously within the divergent area of this diffuser and compressed into the convergent confines of same, it is thus apparent that the third phase of combustion is achieved.

The gas/steam flow from the third phase diffuser 89 is imparted to an axial flow turbine of orthodox design 10 and manufacture 98 which is installed longitudinally and immediately aft of the third phase diffuser. In order to provide a rotational power media for the provision of rotationally induced electricity, a plurality of generators 99 are arranged and installed equilaterally at equidistant intervals around the after-burner tube 100. The mechanical drive shafts 101, which impart rotational force to the generators, actually receive their respective motion from planetary gears 102 which are installed within fixed bearings 103 at equi-distant intervals around the turbine sun gear 104 while the mating annulus gear 105 revolves around the outer peripheral points of contact to all the planet gears 102. As hereinbefore described, the transverse elevation or cross-sectional layout of the locations of the generators 99 are shown as being positioned around the central gas efflux afterburner tube 100 within one of the propulsion units. It is noted also that all the generator drive shafts 101 actually extend further rearward beyond the generators 99 in order to supply rotational motion to the multiple distributors 106 which direct the individual electric current supply from the multiple coils 107 toward the individual circuits 108 for further supply to the ultra-high frequency spark flow circuitry within the electro-infusion system of phase six of one of these propulsion units. The generator drive shafts also serve to drive the turbo-alternators 109 which are installed to provide a constancy of electric power for starting and to augment the generators.

The actual after-burner tube 100 constitutes the fourth phase of combustion into which a further supply of kerosene from the pumps on the main deck imparts a high pressure kerosene flow to the kerosene after-burner injectors 110 in conjunction with a supply of highly compressed air from the air compressors on the main deck. The compressors also impart high pressure air via air pipes 111 to the air injectors 112 in order to augment a parallel flow to the gas/steam stream within the after-burner tube 100. When this gas/steam mixture is burned equi-laterally and compressed within the aft confines of this tube, then the fourth phase of combustion is achieved.

Reference is now to be had to FIG. 7 wherein the further phases of combustion are shown. The fifth phase of combustion takes place within a hemispherical chamber 113 into which a high flow rate of insular water is pumped from its respective high pressure water accelerator pumps 114 via their water injector nozzles 115 in order to convert the gas/steam flow into a steam/gas flow when the resultant pressurized mixture is compressed within the confines of this chamber's aft orifice 116.

The electro-infusion system constitutes the sixth phase of combustion wherein the actual electro-infusion tube 117 is simply a tapered tube, longitudinally placed from fore to aft and secured to the aft or tail orifice 116 of the fifth phase hemispherical chamber 113 with the smaller orifice of this tube being abut-

tedly sealed to the chamber orifice with the tube's larger orifice being at the rearmost extremity. Into the infusion tube 117, which is lined with a conventional heat resistant industrial ceramic material 118, there is installed a concentrically and helically coiled cable holster 119 which is also coated liberally with the industrial ceramic. The holster 119 contains the numerous circuit feed wires 120 which constitute the individual circuit current supply lines to their respective spark plugs or electrodes 121. The triple phase distribution within each individual circuit includes the means for modulating the current to provide a regulated spark glow between each set of electrodes 121. This will be explained more fully hereinafter with the description of FIGS. 13 and 13A.

In the sixth phase of combustion, it is noted that by far the greatest physical element of the steam/gas flow at entry is high pressure steam due to the admission of insular water prior thereto which super-heats this steam. An electrical infusion system is utilized herein to create a highly energized activity by imparting electrical heat energy to infuse the steam thereby converting it to a gas of ultra-high temperature and to thereby raise its flow rate and pressure. In this system the sparks' flow rate is by an ultra-high frequency set up in circuitry utilizing the multiple coils, distributors and turbo-alternators and imparted to the multiple spark electrodes installed in a concentrically-helical formation in both dimensions, i.e., transverse or cross-section and longitudinal. Thus, since all the sparks are discharged in the form of a high-frequency glow and flowing between their respective electrodes from front to rear inside the electrical infusion tube, a highly efficient and equi-laterally incandescent form of combustion is achieved.

The seventh phase of combustion is created by the steam/gas flow being directed immediately into a further hemispherical chamber 122 wherein liquid oxygen 123 is injected via the oxygen injectors 124 from their supply pipes 125 at intermittent intervals. Similarly, liquid hydrogen 126 is also injected via their respective injectors 127 and supply pipes 128 which are fed from their respective processing plants located on the midship's main deck compartments. The output flow from these injectors 124 and 127 is directed in an equilaterally uniform spray and in parallel flow in relation to the steam/gas flow and then pressurized within the convergent throat 129 at the rear extremity of this chamber. The resultant gas then flows as the jet thrust eflux 130 via the outlet venturi 131.

The injection of processed liquid hydrogen and liquid oxygen as the intermittent additives after the electrical infusion has taken place is designed for the sake of safety and economy. The reason for this is that the envisaged payload of the craft consists largely of passengers rather than a vast chemical plant to process the liquid hydrogen and liquid oxygen at a high flow consumption rate.

As shown in FIG. 7A, the entire combustion phase assemblies throughout the entire propulsion systems are contained and securely withheld by vertical bracing plate members 132 which are longitudinally disposed throughout the entire length of the propulsion systems. The horizontal bracing plate members 133 are so positioned, as shown in FIG. 7A.

It is seen that the plurality of generators and turbo-alternators within the propulsion systems are provided to

produce a sufficiency of electrical current supply for the electrolysis equipment of conventional design in the processing plants in order to obtain liquid oxygen and liquid hydrogen from the spent insular water. This is in addition to providing the necessary electrical supply for the electro-infusion spark electrodes and, of course, the usual electricity requirements for the lighting and power supply for the passengers and crew.

Within the high temperature chambers and tubes of the combustion phases from the fifth phase onwards, the insulation therein is to be industrial ceramics of standard construction and serve to protect the electrical and metallic components from excessive overheating and temperature changes between their inner and outer surfaces.

SPARK ELECTRODE POWER SUPPLY

Reference is now to be had to FIGS. 13 and 13A wherein the circuitry for the power distribution is shown. As illustrated, to provide the electrical power for each of the twin-spark electrodes, a triple phase power distribution circuit is used for each spark system in conjunction with a triple phase generator. The power is fed from the triple phase generator into the triple phase power distribution circuit through three single phase input inductances into three separately tuned phase modulation circuits, as shown in FIG. 13A. The power is then fed through an adjustable balance Wheatstone bridge 'B' for the E.M.F. output to the spark electrodes. A pair of indicating watt meters 'A' and 'C' are interconnected from the Wheatstone bridge.

This power distribution circuit is envisaged to give a complexity of electron reaction from the spark electrodes, thus forming an instantaneous wall of electrical discharge in the electro-infusion tube prior to liquid oxygen and liquid hydrogen injection in the final combustion phase.

Incidentally, the circuitry relating to the spark electrodes is independent, i.e., a self-contained circuit assembly to each pair of electrodes wherein the polarity is relevant and conducive to its own earth wire which completes that circuit. All the circuits' wiring within the electrical infusion assembly is housed within a ceramic coated cable holster which is concentrically installed within the ceramic lined infusion tube of the sixth phase combustion layout. In other words, the independent closed circuits of ultra-high frequency are triple-phase distributed, one after the other, at a firing rate synchronized with the flow rate of the steam/gas passing through the tube. This makes it possible that as many of the molecules as possible within the steam/gas flow shall be affected and activated by the impartation of heat energy from the glowing areas of the ultra-high frequency sparks, which occur within the volume of the electrical infusion tube. The ultra-high frequency can be modulated, if desired.

ANCILLARY EQUIPMENT

IMMERSED GENERATING AND/OR PUMPING PLANT

Referring now to FIG. 8, the side or longitudinal elevation of the foremost two-thirds of one of the propulsion units 137, as already described previously, is shown. The entire propulsion unit is installed upon an alignment of foundation pedestals of reinforced or pre-cast concrete construction 134 which are securely af-

fixed within entrenchments 135, in the sea or river bed 136.

Referring now to FIG. 9, a side elevation is shown of the continuing final and rearmost one-third of the same propulsion unit 137 as similarly installed upon its relative series of foundation pedestals 134. This assembly is arranged for connection to the plants tubular housing assembly 138 which contains the main turbine 139 for direct drive via orthodox couplings to the main electric generator 140 shown in FIG. 9A, and the continuation of the drive shaft 141 to drive electric generators 142 and/or pumps 143 for liquids or fluids, as desired, and to provide respectively electricity via output cables 144 and/or pressurized liquids or fluids 145 via output pipes 146.

It is noted that the plant's tubular housing 138 with its respective insular water flow 64 is connected to the thrust jet efflux orifice flange 147 positioned on the outer periphery of the jet efflux outlet venturi by a plurality of bolts and nuts 148 with a suitable heat resistant gasket 149 affixed between the rearmost periphery of this flange and the plant's foremost periphery on its steam-gas intake orifice 150.

Referring specifically to FIGS. 8A and 9, the outer housings 151 of the propulsion unit and that of the plant 152 are similarly connected by bolts and nuts 153 with a waterproof gasket 154 installed between their respective flanges 155 in order to enable the insular water 64 to flow directly rearwards into the plant housing to serve the purpose of cooling the heated surfaces as hereinbefore explained, which relates to the combustion systems within the propulsion units.

Referring particularly to FIGS. 9 and 9A, it is seen that the principle of this structure is simply to utilize the steam-gas efflux from the propulsion units to impart a rotary motion to the rotor assembly within the main turbine in order to provide rotation further to the main generators and/or pumps which respectively can supply electricity and/or pressurized liquid or fluid via their respective output power cables 156 and/or pipe lines 157 to whatever locations desired beyond the plant's installation.

COMPOSITE RAFT

Referring now to FIGS. 11 and 12 wherein the side and rear elevations respectively of the assembled layout of a plurality of the basic crafts 158 are shown as arranged in quadruple and quadrangle alignments beneath the composite craft main deck structure 158A, this being shown by the plan layout on FIG. 10.

As illustrated in FIGS. 10, 11 and 12, each quadrangular group of the basic crafts is pivotally connected by transverse and longitudinal torsion beams 159 which can pivot around and about their respective central pivot hinge pins 159A which are fitted to the composite craft main deck structure 158A. The extremities of the torsion beams 159 are pivotally connected to their respective hinge pins 160 which are fitted aboard pedestal mountings 160A which form the integral upper portion to their respective quadrangle group turntables 161. This construction enables steerage to be accomplished while conveying their load at the corners formed by the torsion beam layout and their respective quadrangle of basic crafts beneath them. The bases of the turntables 161A are shaped in the form of saddles generally in order to straddle their respective oscillator beams 162 upon which they are borne, with the with-

holding means being their respective pivot pins 161B.

In order to distribute the load of the main deck structure with the payload above and upon it, i.e., to spread the loads equally onto the basic crafts, the oscillator beams 162 are adapted to receive hinges 162A which permit swinging at right angles to the pivot pins in the saddle shaped members. These hinges 162A serve to transmit their upper load onto their respective lower members via their pins thereby imparting their load 10 equi-laterally downwards onto the upper members of turntables 163. The lower members of the turntables 163 are fitted to the basic craft unifying arches 164 which serve to distribute and impart their load towards each individual basic craft 158 via the medium of feet 15 hinges 165 which, in turn, serve to transmit their load downwards further onto their respective basic craft center arches 166. The purpose of these craft arches is to distribute their applied load so as to spread the load onto their respective feet hinge mountings 167 which 20 are installed aboard the centrally mounted turntables 168 mounted upon their respective basic craft 158.

In order to maintain a parallel relationship in the vertical aspect between each pair of basic crafts 158 within each quadrangular group, a plurality of spacer beams 169 are fitted and connected at their extremities by universal joints 170 which permit the necessary swivel and flexibility when the overall craft negotiates very large waves on the high seas.

Referring specifically to FIG. 12, a series of stabilizer 30 vanes 171 are installed between each pair of propulsion units at the stem and stern of each basic craft. The vanes 171 have their axes set in the craft's transverse aspect horizontally and oscillate in a vertically swinging motion below the surface of the ocean in order to assist 35 in stabilizing each basic craft thereby eliminating shock loading in storm conditions.

It is to be noted that in accordance with the present invention it is desirable to have a flexible inter-linked system of load distribution wherein a rocking motion is 40 permitted either longitudinally in a vertically swinging movement or transversely in a vertically swinging movement as alternately applicable to each respective beam member. Throughout the sequence of load-distribution from the composite craft main deck 158A down to each pair of basic crafts 158, which are actually carried by the waves of the river, sea, or ocean, according to locality of operation, it is necessary that the 45 design be such that the weight bearing components are arranged in a succession of distributing members which are pivoted and hinged at alternate levels and at right angles in relation to each other in that this larger water borne craft is composed of a plurality of the craft or crafts as hereinbefore described, and is formed by the 50 containment of an overall main deck structure which may support additional decks, as required. The containment of the main deck structure is such that it is superimposed and counterpoised upon a cross balanced plurality of the basic crafts as already described, with the composite main deck structure being counterpoised by pivot mountings onto both longitudinal and transverse torsion beams at their centers thereby allowing a rocking movement to occur in the torsion beams. The outer extremities of the torsion beams may be 55 hinged onto pedestal platforms with integral turntables to transmit the load of the structure onto quadrangle groups of the basic crafts via saddle shaped base elements which are pivoted to and upon oscillator beams 60 65

which likewise have turntables hinged onto their outer extremities.

The load distribution at these locations is thus diverted via the oscillator beams into two directions while the turntables allow for steering to be accomplished and the pivots and hinges can thus permit oscillation to the saddle base elements and the torsion and oscillator beams. The load distribution henceforth is diverted down onto unifying arches which extend outwards and downwards onto the basic craft center arches via feet hinges at the lower extremities of the unifying arches. This results in the load distribution being finally borne by each basic craft center arch which is installed amidships onto its relevant turntable mounting by feet hinges and also permits oscillation and steering of each respective basic craft.

In order to retain an equi-lateral and equal distance between each set of four basic crafts within each quadrangle, a plurality of spacer beams are connected by universal joints at their extremities onto the upper and lower locations of the sides respective to each neighboring basic craft but in parallel formation. This makes it possible that when the entire composite craft negotiates waves on the high seas or during a heavy ocean swell, the parallel spacer beams are then allowed to form a parallelogram by their locational inter-relationship with each other in conjunction with the sides of their respective basic crafts.

BOOST UNIT FOR EACH PROPULSION SYSTEM

Reference is now to be had to FIG. 14 wherein a means for boosting the propulsion power for each propulsion system abroad each and every basic craft is shown. The boosting means is provided by the expediency of utilizing the gas jet thrust efflux 130, as shown in FIG. 7, as the intake gas to drive a plurality of high pressure axial flow turbines, which provide rotational force and drive to a plurality of turbo-alternators of conventional design. This results in an imparting of a sufficiency of electricity for the further operation of the electrolysis equipment to produce more liquid oxygen and liquid hydrogen in the processing plants and also, in addition, supplies electricity to a further system of electro-infusion via the media of additional twin spark electrodes in order to impart further electrical heat flow to the pressurized steam/gas in which even more insular water is utilized and into which further liquid oxygen and liquid hydrogen is ultimately injected. This will provide an even greater pressurized gas jet thrust efflux from the final outlet venturi in a similar manner to the methods as described hereinbefore in sequence from the outlet of the third phase diffuser to the seventh phase of combustion.

The insular water jacket tube 172 surrounds the gas jet efflux tube 174 at the rearmost extremity of each of the basic propulsion systems. The actual means of coupling the boost units are afforded by circuit coupling flanges 173A and 173B to both the insular water jacket tubes and their internal gas jet efflux tubes. The continuation of the boost unit insular water jacket tubes 173C extends rearwards as the longitudinal outer periphery of each of the respective boost units, while the gas jet efflux continues rearwards within the collector input tube 175 and guided towards the intake of the high pressure axial flow turbine 176 which utilizes the rearward thrust of the gas stream to convert the power into a rotational motion mechanically. This imparts rotation

to the annulus mating gear 177 and henceforth onto the planet gears 178 which, in turn, impart mechanical rotation to the turbo-alternator drive shafts 179 which serve to drive the rotor members within the first stage

- 5 turbo-alternators 180A and drive shafts 181A to the second stage turbo-alternators 180B and also the distributor couplings 181B and distributors 181C, which are installed to provide individual circuitry for each and every pair of spark electrodes 186 within the electro-infusion tube 187, as shown in FIG. 15. The turbo-alternator drive shafts and turbo-alternators, distributor couplings and distributors are arranged and installed longitudinally around the central gas tube 182 which serves to direct the flow of gas from the turbine 15 rearwards to the expansion chamber 185, as shown in FIG. 15.

Referring now to FIG. 15, it is seen that the gas tube 182 directs the gas flow into the expansion chamber 185 into which is also injected the warm insular water 20 from water pumps 183 installed within the insular water jacket tube 173C via the water injector nozzles 184. The addition of this water in the form of a high speed mist spray can thus be integrated into the expanding action of the gas and then compressed further 25 within the narrow confines of this expansion chamber at its rearmost extremity prior to the entry of the gas into the electro-infusion tube 187 in which the pairs of twin spark electrodes 186 are installed in a helically concentric formation as so described for the similar electro-infusion assemblies within the propulsion systems, as hereinbefore described. The circuit layout for the spark electrodes are substantially described specifically with reference to FIGS. 13 and 13A. The result of this electro-infusion as imparted to the steam/gas flow 30 is in the provision of an increase in temperature. This is caused by the electrical heat energy expanding the molecules of oxygen and hydrogen content of the water injected as described with regard to the expansion chamber injection immediately prior to this electro-infusion assembly.

When this ultra-heated gas departs at an increased speed from the larger orifice of this electro-infusion tube 187 at its rearmost extremity, the gas is thus directed into the hemispherical combustion chamber 190 35 in which are injected simultaneously the concurrent atomized sprays of liquid hydrogen via their respective injectors 188 and liquid oxygen via their respective injectors 189 at entry locations adjacent to the entry of the steam/gas. The injection of oxygen and hydrogen is 40 parallel to the gas flow. When the resultant ignition and expansion of this hydrogen and oxygen occurs within this hemispherical chamber 190 and compressed within the exit orifice of same at its rearmost extremity, and increase in pressurized flow of the gas is thus incurred. This increase occurs prior to the speed of this gas being 45 increased even further via the wider orifice of the outlet venturi 191 at its rearmost extremity.

Provision for the further coupling of more boost units and/or electrical generating plants and/or liquid pumping plants is possible by the expediency of insular water jacket tube flanges 192 and 193 with delivery duct for the spent insular water 194. The gas efflux coupling flanges 195 and 196 may also be used and are located 50 further aft and below the tail outlet orifice blanking off cap 197 and are similar to the caps 45 within the propulsion systems as shown in FIGS. 1 and 2.

I claim:

1. A propulsion unit for propelling a marine craft comprising elongated housing means, a first combustion zone means centrally positioned within and spaced from said housing means and adjacent the forward end of said housing means, said first combustion zone means having an inlet end and an outlet end, means to feed fuel, water and air under pressure into the inlet end of said first combustion zone forming a pressurized combustible mixture therein, incandescent combustion means for effecting the combustion of said formed mixture in said first combustion zone means with said resulting mixture passing out through the outlet end of said first combustion zone means, at least one other subsequent combustion zone means having an inlet end and an outlet end centrally positioned within and spaced from said housing means and connected at its inlet end in axial alignment to the outlet end of said first combustion zone means for receiving the combusted mixture from said first combustion zone means, said other combustion zone means including divergent-to-convergent and convergent-to-divergent diffuser means to effect further pressuring of said combusted mixture, means to feed fuel, air and water into said other subsequent combustion zone means under a pressure greater than the pressure employed in said first combustion zone means for admixture with said combusted mixture, said gas, water and air mixture being subjected to combustion in said subsequent combustion zone means to build up a gas and steam flow mixture under an increased pressure and flow rate for passage from the outlet end thereof, axial flow turbine means having an inlet end connected to said other combustion zone and outlet end connected to an afterburner means centrally positioned within said housing means in spaced relation therefrom and connected at its inlet end in axial alignment to the outlet end of said turbine means, means driven by said turbine means to generate electric power means to feed gas and air under high pressure to said afterburner means for admixture with said gas and steam mixture therein, said mixture being subjected to combustion adjacent the outlet end of the afterburner means and being passed thereafter from the outlet end of said afterburner means in a compressed state, gas and steam compressible chamber means having an inlet end and an outlet end centrally positioned within and spaced from said housing means and connected at its inlet end in axial alignment to the outlet end of said afterburner means for receiving said gas and steam mixture under pressure therefrom therein, means to feed water under high pressure into said compressible chamber means to convert said gas and steam mixture into a steam and gas mixture, said

steam and gas mixture being further compressed in the compressible chamber means adjacent its outlet end thereof, incandescent combustion chamber means having an inlet end and an outlet centrally positioned within said housing means in spaced relation therefrom and connected at its inlet end in axial alignment to the outlet end of said compressible chamber means for receiving the highly compressed steam and gas mixture therefrom, incandescent means for effecting the combustion of said steam and gas mixture to raise the pressure and flow rate of said steam and gas mixture, a final combustion zone means having an inlet end and a jet thrust effluent end centrally positioned within and spaced from said housing means with the inlet end thereof being connected in axial alignment to the outlet end of said incandescent chamber means for receiving the combusted steam and gas mixture therein, injection means for injecting liquid oxygen and liquid hydrogen under pressure into said final combustion zone means for admixture with said combusted steam and gas mixture, said mixture being pressurized and subjected to combustion in the aft end of said final combustion zone means with the resulting gas flow passing through the outlet end thereof as the jet thrust effluent the spacing of said respective combustion zone means, compressible chamber means, combustion chamber means, and said axial flow turbine means from said housing means forming an axially extending spacing therebetween, and means for passing water through said formed spacing to effect the cooling of said propulsion unit.

2. A propulsion unit in accordance with claim 1 wherein said means for passing the water through the formed space include means to draw the water on which the marine craft is moving as the water for use in said unit.

3. A propulsion unit in accordance with claim 2 wherein the means drawing the water comprise valve means having a plurality of cone means having openings formed therein positioned in superimposed relationship with respect to one another, and means to rotate the cone means with respect to one another whereby the said cones are positioned in alternately fixed and rotationally movable sequence with respect to one another to control the rate of flow of water into the formed spacing.

4. A propulsion unit in accordance with claim 2 which further includes means for feeding the water under pressure, where needed, for admixture with the gas and air in the operation of the propulsion unit.
